UNITED STATES PATENT OFFICE

2,373,018

HOSPITAL BED

Clarence Anthony Deckert, Jackson Heights, N. Y.

Application May 8, 1942, Serial No. 442,204

5 Claims. (Cl. 5—69)

The invention relates to hospital beds and has for its object to provide a device of this kind comprising a head section, a foot section, connected together by two intermediate sections, all of said sections being hingedly connected and to provide operating means in connection with all of said sections whereby said sections may be placed in different angular positions in relation to each other for supporting the body of a patient in various positions for bed pan and treatment operations.

A further object is to provide a hospital bed formed from hingedly connected sections comprising a body supporting head section connected together by hingedly connected intermediate sections and means cooperating with all of said sections whereby the head and intermediate sections can be adjusted to various angles in relation to each other for supporting the body for various purposes and in various positions for attention and treatment purposes, or to incline the body with the head and foot sections in the same plane, but in an inclined position, for instance for the shock position, the "Trendellenberg" and the "Fowler" positions, and at the same time the intermediate sections are in V formation for forming a transverse depression in the mattress for preventing slipping of the body on the bed, and relieving the patient of any muscular tension, due to the patient's body being in an inclined position. This transverse depression, whereby the patient is anchored by the buttock fitting into the said depression, represents an entirely new and radical departure from the "Trendellenberg," "Fowler" and postural drainage positions now obtainable on conventional beds. With the patient thus anchored it is possible to incline the patient to a greater angle, thus increasing the (therapeutic) efficiency of the various positions mentioned, while at the same time giving the patient a sense of security which will prove valuable in preventing nausea, especially of patients in a semi-conscious state.

A further object is to provide a hospital bed having a relatively long head section to completely support the body above the buttock and raise the buttock to a position above an inclined intermediate section so that a bed pan may be easily placed under the buttock without the necessity of lifting the patient.

A further object is to provide a hospital bed comprising a head section, two intermediate sections and a foot section, all transversely hinged and means whereby all of said sections can be placed in the same plane or in various angular positions in relation to each other.

A further object is to provide a hospital bed comprising a head section connected to a foot section by an intermediate section and means whereby the head section may be elevated with

the back and head of a patient entirely supported thereon, to a position where the intermediate section will incline upwardly towards the head section, thereby allowing a bed pan to be placed beneath the patient in a position for use, and at the same time obviating the labor involved in lifting the patient, now experienced with conventional hospital beds.

A further object is to provide means whereby the head section may be adjusted to various angles, and independent means whereby the foot section may be adjusted to various angles.

A further object is to provide the side rails of the bed with brackets and to hingedly connect the adjacent ends of the intermediate sections to said brackets and the outer ends of the intermediate sections to the head and foot sections, and to provide elevating and adjusting means for all of the various sections.

A further object is to provide downwardly offset transverse braces for the intermediate sections.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a side elevation of the bed showing the head section elevated in dotted lines.

Figure 2 is a top plan view of the bed.

Figure 3 is a vertical transverse sectional view taken on line 3—3 of Figure 1.

Figure 4 is a vertical transverse sectional view taken on line 4—4 of Figure 1.

Figure 5 is a vertical longitudinal sectional view through the bed, showing the head section elevated.

Figure 6 is a longitudinal sectional view through the extensible connection of one of the operating shafts.

Figure 7 is a side elevation of a horizontal bed showing the uncomfortable bed pan position as at present used in conventional beds.

Figure 8 is a view similar to Figure 7 showing the various sections lowered to horizontal positions for ordinary use by a patient.

Figure 9 shows a bed adjusted to a semi-Fowler position.

Figure 10 shows a bed adjusted to a bed pan use position with the weight of the upper portion of patient's body supported on the head section.

Figure 11 shows the bed adjusted for bed pan use with the bed pan in position.

Figure 12 shows the bed adjusted for supporting the patient in best defecation position.

Figure 13 shows the bed adjusted for support-

ing the patient in a therapeutic position for enema treatment.

Figure 14 shows the bed adjusted for supporting the patient in a raised position for emergency operation, and inclined towards the head for shock purposes.

Figure 15 shows the bed adjusted for supporting the body of the patient in full shock position, or what is known as "Trendelenburg" position.

Figure 16 shows the bed adjusted to support the body of the patient in a position known as full "Fowler" position.

The present application is a continuation in part of my application, Serial No. 396,921, filed June 6, 1941.

Referring to the drawings, the numeral 1 designates the head frame of the bed, and 2 the foot frame. The head and foot of the bed are connected together by side rails 3, forming a rigid structure. Secured to the outer sides of the side rails 3 by means of rivets 4 are upwardly extending plates 5. Disposed above the side rails 3, preferably in registry therewith are the head section 6, the intermediate section 7 and the foot section 8 of the adjustable parts of the bed.

The foot section may be formed in two sections, hingedly connected at 9 so a leg adjustment may be obtained and the various positions shown in Figures 7 to 16 inclusive for the purposes hereinafter set forth. The foot end of the intermediate section 7 is hingedly connected at 10 to one of the ends of the plates 5 and adapted to be hingedly moved upwardly to the dotted line position shown in Figure 1, and the full line position shown in Figure 5 for elevating the section 6, hingedly connected at 11 to the end of the section 7. The opposite sides of the intermediate section 7 are connected together by downwardly arched transverse braces 12, one of which forms the pivotal point 10, and these braces, in turn, are further braced by longitudinally extending braces 13. Connected to one of the braces 12 at 14 is an operating shaft 15 which extends to the foot 2 of the bed and has an extensible connection 16 therein. The extensible connection 16 includes a threaded member carried by the shaft section 15a, and this threaded member is designated by the numeral 17. When the shaft 15a is rotated, a push or pull is imparted to the shaft 15 for raising or lowering the intermediate section 7. Shaft 15a is rotatably mounted in a rock sleeve bearing 18, pivotally mounted at 19 in a bracket 20 carried by the foot 2 of the bed and terminates in a crank 21, adapted to be grasped by the operator for raising or lowering the intermediate section.

The head section, which is hingedly connected at 11 to the intermediate section 7, is raised or lowered to the proper elevation or inclination by means of rollers 22 engaging the under side of the frame 6, and these rollers are carried by the arms 23 of a U-shaped rock frame 24. The rock frame 24 is pivotally mounted at 25 in downwardly extending brackets 26 carried by the side rails 3 and one of said arms 23 is provided with an upwardly extending plate 27 to which is pivotally connected at 28 a control shaft 29, which shaft extends to the foot of the bed and terminates in an operating crank 30. Shaft 29 is provided with an extensible connection 31, similar in construction to the connection 16, therefore it will be seen that by operating cranks 21 and 30 the intermediate and head sections 7 and 6 can be easily and quickly adjusted upwardly or downwardly and the body of the patient can be raised so a

bed pan can be placed under the buttock. Such a bed pan is disclosed in my application, Serial 396,922, filed June 6, 1941.

A conventional form of mattress 32 rests on the bed sections 6, 7, and 8, and it will be seen that this mattress will conform to the adjustment of the various sections as clearly shown in Figures 7 to 16 inclusive, and at the same time, with the body of the patient resting on the portion of the mattress carried by the adjustable section 6, the mattress will not become displaced during the body elevating or lowering operation.

After the sections have been properly adjusted as shown in Figure 5, the bed pan 33 is placed under the buttock 34 of the patient with the extension 35 of the bed pan extending upwardly above the buttock and in close engagement with the mattress 32. It will be seen, during the elevating operation, the weight of the body is mechanically lifted, and it will not be necessary for the nurse to lift the body as is now the common practice when a bed pan is used.

It will be noted that the foot section 8 has hingedly connected thereto at 9, a second foot section 8a and these sections may be adjusted upwardly by means of a U-shaped frame 34a having arms 35a extending towards the foot 2 of the bed and pivotally connected on the hinging points 9. Where the U-shaped bracket 34a merged into the arms 35a, rollers 36 are provided which have a trackway on the upper sides of the side rails 3 of the bed, and it will be seen that when the U-shaped bracket 34a, Figure 5, is moved in the direction of the arrow a, the hingedly connected portions of the foot sections 8 and 8a will be moved upwardly, therefore it will be seen that a leg adjustment may be obtained when desired. The U-shaped bracket 34a is operated by means of a shaft 37 having an extensible connection therein, designated by the numeral 38, and a similar construction as the connection 16.

Shaft 37 terminates in a crank 39 at the foot of the bed. It will be noted that the adjustable sections 6, 7 and 8 are in registry with the side rails 3 of the bed, therefore it will be seen that it will not be necessary to materially vary the construction of a conventional form of hospital bed now in use, however applicant does not limit himself to such an application.

The foot section 8a is held and braced in various elevated positions by means of hingedly mounted arms 40 carried by the foot section 8a and which arms are provided with lugs 41, received between the stop lugs 42 carried by the pivoted bar 43, one end of which is pivoted at 9 and the other end terminates in a traveller sleeve 44, which is slidably mounted on the traveller bar 45 carried by the bed rails 3, therefore it will be seen that the foot section 8a may be held in the various raised positions as shown in Figures 10 to 16.

Sections 6 and 8a are preferably provided with rollers 46 which ride on the side rails 3.

Referring to Figures 7 to 16 inclusive, where in the many desirable positions of the bed are shown, Figure 7 displays and shows the uncomfortable position now commonly in use with bed pans, and it will be obvious with a straight bed it will be necessary for the nurse to lift the body to insert the bed pan 33. With applicant's device the weight of the body is supported and mechanically lifted on the head section 6 as shown in Figure 11.

Figure 8 shows the normal horizontal position of the bed, with all the sections lowered.

Figure 9 shows the parts of the bed adjusted to semi-Fowler position, a position now obtainable in a standard bed and shows that the new device for which this application is being made does not interfere with this position mechanically.

Figure 10 shows the bed in a position for insertion or removal of a bed pan, also the position available for cleaning of buttock and anal regions. The knees are supported, if desired, by bed clothing tucked under the mattress, which is a matter of nursing technique, and which has been found practical and efficient. The insertion of the bed pan is practical in the position shown because of the giving of the mattress and of the muscular portion of the patient's buttock, and as the dead weight of the patient is supported above the buttock towards the patient's head and on the section 6.

Figure 11 shows the bed adjusted and the action of fitting the bed pan 33 to the patient by adjustment of the lower sections 8 and 8a. The adjustment of sections 8 and 8a is a manipulation already familiar to the nurse, section 8 being lowered or raised by means of control handle 39, while 8a is raised or lowered in relation to section 8 by manual means.

By hingedly moving the sections 8 and 8a of Figure 11 upwardly the bed pan can be forced towards the head section 6, and be securely held in position.

Figure 12 shows the bed adjusted for positioning the patient in the best defecation position with back raised to maximum position. The patient may be completely relaxed by placing a pillow under the knees, and bringing up the knee adjusting sections 8 and 8a a little higher.

Figure 13 shows the bed adjusted in a therapeutic position for enema treatments; and the use of a pillow under the knees is desirable for complete relaxation. The complete relaxation of all muscles, plus the gravity coefficient on the descending colon of any patient which is obtainable by lowering the head section 6 and upper body of the patient will tend to make all enemas given much more efficient. The complete relaxation of abdominal muscles will enable the patient to retain fluid enemas much more efficiently and easily, and at the same time reducing the necessity of using large amounts of fluid for the enema treatment.

Figure 14 shows the bed adjusted for supporting the body in an elevated position for emergency operation, and it will be seen that the patient can be raised or lowered to any level desired with the additional possibility of lowering the upper part of the body to shock position which is highly desirable in most operations.

Figure 15 shows the bed adjusted to full shock position (Trendellenberg). The position is also more efficient for postural drainage than that obtained on regular Trendellenberg or Fowler beds. This is because of the transverse chamber in which the buttock of the patient is disposed; relieving the patient of any muscular tension, due to the patient's body being in an inclined position. A greater angle of inclination of the patient's body is now obtainable, due to this transverse depression anchoring the patient, thus increasing the therapeutic efficiency for postural drainage.

Figure 16 shows the bed adjusted in a reverse

position to the full shock shown in Figure 15 and to the full Fowler position. In this position the buttock fits into the central position, and the body is inclined at any angle for postural drainage.

From the above it will be seen that an adjustable hospital bed is provided which may be easily adjusted for supporting the body of a patient in various positions; for bed pan; therapeutic or operating purposes, and the body is mechanically lifted, thereby obviating the necessity of manually lifting the body, particularly when using a bed pan.

The invention having been set forth what is claimed as new and useful is:

1. A hospital bed adapted to support a patient in an inclined position with the buttock of the patient in a transverse depression and the entire body supported, said bed comprising a stationary frame, a mattress supporting frame, said mattress supporting frame comprising a head section of a length equal to or greater than the distance from the buttock of the patient to the head of the patient, a foot section, an inner section hingedly connected to the inner end of the head section and to the stationary frame, an inner section hingedly connected to the inner end of the foot section and hingedly connected to the stationary frame and means for adjusting all of said sections whereby the head and foot sections may be elevated and inclined in various planes and the inner sections angularly positioned for forming the buttock receiving transverse depression.

2. A device as set forth in claim 1 including means whereby said head and foot sections may be inclined to various planes after an elevating operation on the hinged connection between the inner ends of the inner sections and the stationary frame.

3. A device as set forth in claim 1 wherein the means for elevating and hingedly moving the various sections is carried by the stationary frame and independently cooperates with said hinged sections.

4. A device as set forth in claim 1 including brackets carried by the opposite sides of the stationary frame, the inner ends of the inner frame sections being hingedly mounted on said brackets.

5. A hospital bed adapted to support a patient in an elevated horizontal plane above a stationary bed frame or in an inclined elevated position above the bed frame with the buttock of the patient in a transverse depression for preventing longitudinal slipping of the patient when in inclined position, said bed comprising a stationary bed frame, a four-section mattress supporting frame above the stationary frame, said mattress supporting frame comprising a head section of a length equal to the distance between the buttock of the patient and the head of the patient, a foot section, the two other sections being interposed between the head and foot sections and having their outer ends respectively hinged to said head and foot sections, the inner ends of said last named sections respectively being hingedly connected to the stationary frame and means for adjusting all of said sections whereby the head and foot sections may be elevated for raising the body of the patient and the other sections placed in angular relation to form the transverse buttock receiving depression.

CLARENCE ANTHONY DECKERT.
